RAYMOND DUBOIS, OF TOULON, FRANCE

ELECTRIC-ARC-LAMP CATHODE WITH ROTARY FLAME AND STATIONARY CRATER

Application filed May 14, 1925, Serial No. 30,205, and in France February 27, 1925.

Arc lamps constituted by a combustible conductive anode from which an arc is struck ending in an incombustible cathode, generally of metal and in the shape of a ring, are all ready known.

The regularity of such arcs in the case of a current of above 15 amperes may be obtained by imparting a quick rotary motion to the flame which then turns around the anodical crater. The anode may be constituted by an appropriate carbon and it is cut so as to form a cavity having a regular shape. The rotary motion preferably produced by the action of a magnetic field is only possible where no imperative cause exists to render the arc stationary at a particular point of the cathode, this always taking place when a point of the region where the arc may be produced reaches a temperature such that the thermionic emission is more abundant there than at the neighbouring points. The arc then remains stationary at this point; on the other hand, it being necessary to thoroughly cool the cathode in order to prevent it from melting, this cooling must be effected. By currents of 25 amperes for instance, cooling by means of running water produced without any special care allows of obtaining a continuous and rapid rotary motion. Things are different in the case of higher current values or when cooling by means of air. The proper rotation of the flame cannot be produced from 20 amperes upwards with a cathode cooled only by air passing through it. The flame follows a circumferential path even with a discharge of large quantities of air under pressure, the flame remains stationary at a point which is rapidly consumed and cannot be avoided.

This invention relates to a new type of cathode which requires for its cooling the minimum quantity of a fluid, liquid or gas such as air at any desired pressure.

The cathodes constructed according to my invention are distinguished essentially in that the inner circulation of the cooling medium is produced so as to maintain the same temperature whatever the considered diametrical plane may be, in other words, every position that the flame is capable of occupying ends at a point of the cathode where the temperature

is the same whatever the considered radius may be. Accordingly the cathode must first of all have the shape of a figure of revolution but this condition which generally obtains in the existing cathodes is not sufficient; in fact 55 the circulation of the fluid must also have this same axial symmetry, that is to say in the region to be cooled, the circulation of the fluid must be such that the isothermal curves are all of them circumferences centered upon the 60 axis of the cathode. In order to fulfill this requirement, the stream lines of the fluid in the region to be cooled must be all geometrically identical to each other and susceptible of being represented by the positions taken successively by the same line caused to revolve about the symmetrical axis of the cathode. 65

The appended drawing shows by way of example, several embodiments of the principles above cited.

Fig. 1 is a sectional view through the middle part of a cathode with symmetrical cooling around the axis.

Fig. 2 is a similar view of a cathode of the standard type with circumferential circulation. 75

Fig. 3 is a sectional axial view for the same cathode as in Fig. 2.

Figs. 4, 5, 6 and 7 are sectional views showing other cathodes based on the same principle as that of Fig. 1.

Fig. 8 is perspective view of a portion of Fig. 7.

Fig. 9 is a perspective view of the type Figs. 5 and 6. 85

In the mode of execution shown in Fig. 1, the cathode is constituted by a piece of copper 1 turned in a lathe, hollowed out and provided at the centre with an edge 2 around which rotates the arc 6 struck from the positive crater 7. The thickness of the metal in the middle part determines the temperature to which the point where the flame strikes out is brought, it must be determined according to the conditions of working of the arc, and is of about 2 millimeters for 25 amperes. A partition wall formed by a disc placed at right angles to the axis of the cathode divides the recess 4 hollowed out in the part 1 in two collectors or channels, 8 and 9 respectively 90 95 100

for the admission and the discharge of the fluid. The cooling is ensured by the passage of the fluid, in the direction indicated by the arrows 4, in the shape of a uniform sheet 5 through the region 5 directly in contact with the region 2 where the heat is supplied. It is not necessary that the supply main carrying the fluid to the inlet collector and the discharge main for the other collector should 10 have the shape of a figure of revolution if the section of the passages 8 and 9 is large enough to cause the flow of the fluid to slow down relatively to its rate of flowing in the region of passage 5 where the section must be much 15 smaller. In this manner the symmetry of the stream lines is not practically altered in the important region even in case of the fluid being admitted and discharged through the same tubes, as in the arrangement shown in 20 Fig. 7.

It is to be noted that a cathode of this type differs essentially from cathodes simply hollowed out such as the one shown in diametrical section in Fig. 2 and in transverse section in Fig. 3. In this cathode which is cooled by means of a circumferential circulation, a point located near the inlet, P for instance, is systematically at a lower temperature than a point located near the outlet, such 25 as Q for instance. Even when the cooling fluid used is water, the difference may be over 100°, as it suffices that the arc should slow down systematically in the region of the highest temperature to bring it to a degree of 30 heat such that the water will be vaporized at that point. Calefaction then allows this region to become overheated. When the cooling is effected by means of a gas, the difference 35 of temperature between the points P and Q easily reaches 200 degrees. Contrary to that which obtains in the kind of cathodes already known of which the inconvenience has been shown, the hot middle region receives only cold fluid or at least fluid having 40 a uniform temperature while in the cathodes of the type shown in Fig. 1, that is where the circulation is radial, no advantage is given to any direction and consequently the flame 45 has no tendency to remain stationary at any point in preference to another.

Fig. 1 of the annexed drawing is merely an example of possible embodiments of my invention.

Fig. 4 shows another embodiment which 55 may be constructed without any difficulty and is specially advantageous even in the case of cooling effected by air. In this last figure the same numerals designate the same parts as in Fig. 1.

In this mode of execution the partition wall 60 3 is no longer separated from the part 1, it is made integral with it and its middle part 5 is perforated with a great number of identical holes 10 in lieu of the annular passage 5, 65 Fig. 1. The distances between the holes are

reduced to a minimum consistent with the resistance of the wall or partition.

In some cases, the section of the collectors may be too small relatively to that of the holes, nevertheless the same discharge may 70 be obtained in all the holes by recurring to the following contrivance. The partition wall is put out of shape by distortion as will be seen in Fig. 5 in such a manner that the section of the collectors varies progressively, 75 the one having a smaller section when the other has a larger one. This large section is then placed in front of the admission to the discharge tube, the fluid inlet tube being placed in front of the greater section of the 80 other collector upon the same diameter. This arrangement is shown in Fig. 7. In this manner all the trajectories of the fluid through the different holes are equal as regards their length and the resistance offered to the passage of the fluid. The size of the holes must remain small enough for the principal loss of charge to take place during the passage therethrough, the loss in the collectors being 85 much smaller. The normal working is thus 90 the same in all the holes notwithstanding the speed acquired by the fluid flowing in the inlet collector this speed tending to favour the nearest holes.

Certain modifications as indicated hereafter may be made in the construction in order to improve the type of cathode above described.

1. The outline of the middle section is such that the luminous field is largely open, to this effect the angle of the cone directed towards the front is very large it may be at least of 110 degrees.

2. The back part in the direction of the crater is plane and perpendicular to the axis, 105 or conical and having an angular opening or more than 120° in order to prevent the arc from getting away from the interior edge 2 of the cathode. In fact the flame always tends to take the position which gives it the 110 minimum length and this outline causes the length of the arc to increase very rapidly when it leaves the middle edge.

3. The width of the edge 2 upon which the arc revolves increases with the strength of the 115 lamp current because it determines the temperature reached by the points where the arc is struck: for 10 amperes for instance, the edge must be sharp and for 25 amperes it must be formed by a truncated bevel having a 120 width of about 1 mm. calculated parallelly to the axis.

4. It is advantageous to be able to replace without any difficulty the region in which the arc revolves and which is susceptible of 125 wearing out slowly. To this effect the cathode may be made removable. Fig. 7 shows a diametrical section of a removable cathode. A stationary part comprises the cylindrical bearing 11 and its pipings 12 and 13. The 130

removable element may be constituted by the element shown in Figs. 5 and 6. The front part and the partition wall 3 may also be made stationary, the only removable element being then the back part 15 comprising the edge 2. The division can be made at 14 by giving to the elements a conical outline which allows of obtaining a tight joint. Plastic joints not represented ensure the tightness of the connection with the bearing 11.

In case of the edge 2 being worn out it may be repaired by metal casting or by autogenous welding when the metal used for its construction is copper, this metal being very suitable for the purpose.

5. The durability of the cathodes can be considerably increased by cutting out the edge 2 in a ring of precious metal unoxydable and less fusible than copper, such as pure platinum for instance. The connection of the precious metal with that of the cathode must be very close in order to preserve the heat conductivity. It may be produced for instance by setting the ring in its recess under a 25 very high pressure or by means of a good heat conducting brazing, such as silver brazing.

It is to be understood that any and all changes in the shape, details, substance and size of the described cathodes within the scope 30 of the claims hereunto appended may be resorted to without departing from the principle of my invention.

I claim—

1. A stationary, hollow, ring-shaped cathode for rotary flame arcs having a partition therein perpendicular to the axis of symmetry of the cathode and separating the interior of the cathode into two communicating chambers, an entrance orifice in one of said 40 chambers and a discharge orifice in the other chamber, said partition being locally distorted at the entrance and discharge orifices.

2. A stationary, hollow, annular, conical cathode for rotary flame arcs having a partition dividing the interior of the cathode into two communicating chambers, said chambers communicating adjacent the central edge of the cathode, cooling fluid supply means for one chamber and fluid discharge means for 50 the other chamber.

3. A stationary, hollow, annular cathode for rotary flame arcs, having an upper and a lower re-entrant conical surface, a partition dividing the space between the surfaces into 55 two chambers and having perforations connecting the two chambers adjacent the narrowest space between the two surfaces, means to supply one chamber with cooling fluid and means to discharge said fluid from the other 60 chamber.

4. A cathode for an electric arc with rotary flame and stationary crater which comprises: a hollow ring-shaped cathode, a separating wall perpendicular to the axis of symmetry 65 designed to divide the inner space of the cath-

ode in two collectors; communication openings formed in said wall near the middle part of the cathode to be cooled; an inlet orifice for the cooling fluid opening in one of the collectors and an outlet orifice opening in the 70 other collector.

5. A cathode for an electric arc with rotary flame and stationary crater which comprises a hollow ring-shaped cathode the section of which is constricted towards the middle so as 75 to provide a large opening towards the front and a plane region in the direction of the crater in order to localize the arc towards the middle, a partition wall dividing the interior of the cathode in two collectors, an inlet open- 80 ing for the cooling fluid provided in one of said collectors, an outlet opening in the other collector and means to cause the cooling fluid to pass from one collector to the other in contact with the part of the cathode to be cooled. 85

In testimony that I claim the foregoing as my invention, I have signed my name.
